UNITED STATES PATENT OFFICE.

THOMAS J. STEARNS, OF BOSTON, MASSACHUSETTS, ASSIGNOR TO THE ROXBURY CARPET COMPANY, OF SAME PLACE.

DESIGN FOR CARPETS.

Specification forming part of Design No. 8,104, dated June 15, 1875; application filed June 8, 1875.
[Term of Patent 3½ years.]

CASE II.

To all whom it may concern:

Be it known that I, THOMAS J. STEARNS, of Boston, in the county of Suffolk and State of Massachusetts, have invented a certain new and original Design for Carpets, of which the following is a specification:

The nature of my design is fully represented in the accompanying photographic illustration.

What I claim as my invention is—

A design for a carpet, as represented in the accompanying photographic illustration.

In testimony whereof I have signed my name to this specification in the presence of two subscribing witnesses.

THOMAS J. STEARNS.
